UNITED STATES PATENT OFFICE

WILLIAM M. DRENNON, OF ANAHEIM, CALIFORNIA, ASSIGNOR OF ONE-HALF TO EDWARD BENNER, OF FULLERTON, CALIFORNIA, ONE-FOURTH TO WM. J. M. HEINZ, AND ONE-FOURTH TO E. F. GANAH, BOTH OF ANAHEIM, CALIFORNIA

FOOT-CONTROLLED HAMMER

Application filed April 18, 1928. Serial No. 270,959.

This invention relates to devices used for striking blows in a rapid successive manner.

One of the objects of this invention is to provide a simple device in which a hammer is actuated by means of a rotating shaft.

Another object is to provide a loosely suspended hammer-head against which material may be held from below and against which a hammer bolt may strike from above.

10 Other objects will appear from the following description and appended claims as well as from the accompanying drawing, in which—

Fig. 1 is a side elevation of a simple machine actuated by an electric motor in a frame structure and controllable by a foot-pedal in accordance with this invention.

Fig. 2 is a fragmentary detail front elevation of the connection between the rotating shaft and the hammer bolt.

Fig. 3 is a fragmentary detail vertical mid-sectional view of the hammer mechanism.

Fig. 4 is a fragmentary detail vertical mid-sectional view of the anvil mechanism.

25 As illustrated in the drawing, the frame 5 is designed to support an electric motor 6 in its upper structure. A flexible coupling 7 of any well-known type is inserted between the electric motor and the main shaft 8. At the free end of the shaft 8 a disk 9 carries the crank-pin 10. A connecting rod 11 connects the pin 10 of the shaft 8 with the hammer bolt 12.

The head 13 on the upper arm 14 of the frame 5 carries the hammer mechanism which is illustrated more clearly in detail in Fig. 3. A sleeve 15 is inserted from the top until the shoulder 16 abuts against the upper surface 17 of the head 14. The sleeve

40 is threaded about its middle as indicated at 18 to receive the threaded end 19 of another sleeve 20. The sleeve 20 is disposed to abut against the under side 21 of the arm-head 13.

By screwing the sleeve 20 securely over

gaged within the head 13, the sleeve ends 22 and 23 are disposed to project below the arm-head 13. These sleeve ends 22 and 23 are spaced from one another as indicated at 24, whereby the sleeve ends 22 and 23 form the 50 guide for the sleeve portion 25 of the hammer-head 26. The sleeve portion 25 is provided with a slot 27 through which a set screw 28 is inserted to limit the up and down movements of the hammer head 26. 55

The hammer bolt 12 is shiftable within the tube 15 with its lower end 29 abutting against the inside of the hammer-head 26.

By holding any material against the underside of the hammer-head 26, the hammer bolt 60 12 comes into a position to strike upon the inside of the hammer-head 26, and the strength of a stroke increases the harder the material is pressed against the underside of the hammer-head 26. 65

For yieldingly holding material under various pressures against the underside of the hammer-head 26 a suitable mechanism is embodied in the lower portion of the frame structure.

70 The anvil mechanism is controllable by a foot-pedal 30 pivotally connected to the frame structure as indicated at 31. A connecting rod 32 connects the foot-pedal with the lever 33. A free end 34 of the lever serves to support the anvil bolt 35. The anvil bolt is made in two sections telescopically disposed to one another with a spring 36 disposed between the two anvil bolt sections. The upper bolt section 37 is 80 provided with a recess 38 in its upper end, as illustrated more clearly in detail in Fig. 4, to receive a pin end 39 of the anvil 40.

The anvil 40 is hereby made removable and exchangeable. In Fig. 4, for instance, the anvil is shown with a concaved face 41 suitable for certain purposes while other faces may be desirable for other purposes. Various anvil-heads are therefore made applica- 85 90

ble by this removable and exchangeable feature.

A spring 42 connects the free end 34 of the lever 33 with the foot-pedal 30 whereby the foot-pedal is held in its uppermost inoperative position and the lever 33 in its lowermost inoperative position, the anvil being disposed in its lower resting position on the lower arm 43 of the frame structure.

10 When the motor 6 is operated, the hammer bolt 12 is rapidly moved up and down; however, as long as no pressure is applied to the hammer 26, no blow, hammering or striking is produced. A material is placed on the 15 anvil 40 which remains spaced and untouched below the hammer until the foot-pedal is actuated.

As soon as the foot-pedal is actuated or 20 pressed downwardly, the material is gradually brought up against the hammer 26 until the hammer is also lifted with the upward moving material.

As soon as the material is lifted high 25 enough that the hammer-head is also lifted, the hammer bolt 12 is in a position to strike upon the hammer-head 26 against the spring 36 in the anvil mechanism.

The spring 36 should therefore be sufficiently strong and of sufficient length to 30 allow the use of the full strength obtainable from the hammer-head through the striking of the hammer bolt 12 within the limits of the slot 27 in the hammer sleeve 25.

By increasing the pressure upon the foot-pedal 30 to result in a higher lifting of the material placed on the anvil 40 against the hammer-head 26, the blows or the strength 35 of the hammering is also increasing.

Lighter blows may be obtained by releasing the foot-pedal accordingly so as to reduce the pressure against the hammer-head and by holding the material under lighter pressure against the hammer-head so that the hammer bolt may have less influence as 40 it strikes against the inside of the hammer-head 26.

As illustrated in Fig. 2, the longitudinal axis of the hammer bolt 12 is disposed not exactly in line with the transversely disposed 45 axis of the main driving shaft 8, but rather eccentric or sidewise in order that the heaviest stroke of the hammer-head will be accomplished when the crank pin 10 is directly sidewise from the center or axis of the shaft 50 8. This means that when the anvil is forced against the hammer-head, the hammer bolt 12 will hit the hammer-head when the crank pin is in this sidewise position and when the connecting rod is approximately in a straight 55 continuous line with the axis of the hammer bolt, so that the least binding may be expected on the sides of the hammer bolt while this is shifted or pushed into the sleeve 15.

Having thus described my invention, I 60 claim:

1. In a hammer, a frame structure embodying an upper and a lower arm, a shaft with its axis disposed in a horizontal position mounted above the upper arm of the frame, a hammer-head shiftably suspended in the upper arm, a hammer bolt operatively connected with the shaft shiftable within and adapted to strike against the hammer-head, and an anvil disposed in the lower arm of the frame 70 yieldingly shiftable towards the hammer-head. 75

2. In a hammer, a frame structure embodying an upper and a lower arm, a shaft with its axis disposed in a horizontal position mounted above the upper arm of the frame, a hammer-head yieldingly mounted in the upper arm, a hammer bolt operatively connected with the shaft shiftable within and adapted to strike against the hammer-head, and an anvil disposed in the lower arm of the frame 80 yieldingly shiftable towards the hammer-head, the longitudinal axis of the hammer bolt being disposed sidewise from the transversely disposed axis of the shaft as and for the purpose described. 85

3. In a hammer, a frame structure embodying an upper and a lower arm, a shaft with its axis disposed in a horizontal position mounted above the upper arm of the frame, a hammer-head yieldingly mounted in the 90 upper arm, a hammer bolt operatively connected with the shaft shiftable within and adapted to strike against the hammer-head, an anvil disposed in the lower arm of the frame yieldingly shiftable towards the hammer-head, and a stop in the upper arm for 95 limiting the yielding movements of the hammer-head. 100

4. A hammer mechanism comprising a sleeve with an annular shoulder at one end 105 and a threaded portion intermediate its two ends, a second sleeve having a threaded portion in one end to engage with the threaded portion of the first-named sleeve with its free end terminating approximately near the 110 free end of and spaced from the first-named sleeve, a hammer-head having a sleeve portion to slidably shift between the two spaced ends of the previously named two sleeves so that the closed end of the hammer-head extends transversely over the ends of the previously named sleeves, and a hammer bolt shiftably disposed within the first-named sleeve adapted to strike with its free end 115 against the inside of the hammer-head. 120

5. A hammer mechanism comprising a sleeve with an annular shoulder at one end and a threaded portion intermediate its two ends, a second sleeve having a threaded portion in one end to engage with the threaded portion of the first-named sleeve with its free end terminating approximately near the free end of and spaced from the first-named sleeve, a hammer-head having a sleeve por- 125 130

tion to slidably shift between the two spaced ends of the previously named two sleeves so that the closed end of the hammer-head extends transversely over the ends of the previously named sleeves, a hammer bolt shiftably disposed within the first-named sleeve adapted to strike with its free end against the inside of the hammer-head, and a stop for limiting the shifting movements.

10 In testimony that I claim the foregoing as my invention I have signed my name.

WILLIAM M. DRENNON.
